UNITED STATES PATENT OFFICE.

GIDEON POTT, JOHN HOUSTON CASSELS, DAVID YOUNG CASSELS, ROBERT WILLIAMSON, AND ALEXANDER MOODY STUART, OF MOTHERWELL, SCOTLAND.

CENTRIFUGAL MACHINE.

SPECIFICATION forming part of Letters Patent No. 732,220, dated June 30, 1903.

Application filed October 9, 1902, Serial No. 126,616. (No model.)

To all whom it may concern:

Be it known that we, GIDEON POTT, JOHN HOUSTON CASSELS, DAVID YOUNG CASSELS, ROBERT WILLIAMSON, and ALEXANDER MOODY STUART, subjects of the King of the United Kingdom of Great Britain and Ireland, residing at Motherwell, county of Lanark, Scotland, have invented certain new and useful Improvements in Centrifugal Machines, (for which application for patent has been made in Great Britain, No. 19,069, dated August 30, 1902,) of which the following is a specification.

In suspended self-balancing centrifugal machines of the well-known Weston type the step-bearing is situated within the outer revolving spindle, and therefore the said bearing is limited in size by the bore of the outer spindle, and it is also somewhat inaccessible. The object of this invention is to enable the step-bearing in such machines to be readily accessible and to permit of much larger step-bearings being used. For these purposes we make the inner stationary spindle hollow or tubular and pass up through it a central spindle, which is attached at its lower end to the outer revolving spindle of the machine, so as to revolve with it, the upper end of said central spindle being adapted to carry the revolving part of the step-bearing, whose stationary part is attached to the top of the stationary spindle.

The invention is illustrated, by way of example, in the accompanying drawings, in which—

Figure 1 is a sectional elevation of a centrifugal machine whose driving-spindle, step-bearing, and relative parts are constructed in the manner shown to a larger scale in vertical section at Fig. 2, while Fig. 3 shows in vertical section a slightly-modified form of the driving-spindle.

As shown by the drawings, the centrifugal machine is carried in the usual way by a framing *a*, the basket *b* being fitted to rotate within a stationary casing *c*. The basket is attached, as usual, to the hollow revolving spindle *d*, which is driven by a belt-pulley *e* or by a motor or in any other usual way; but the inner stationary spindle *f* instead of being solid and having the usual step-bearing

at its lower end is made tubular, as shown, and has passed up through it a solid central spindle *g*, which is formed with an enlarged plunger-like end piece *g'*, pinned or keyed to the outer spindle *d*, so as to rotate with it. Between the rotating central spindle *g* and the stationary hollow spindle *f* a guide-sleeve or hollow bearing *h* is fitted, as shown at Fig. 2, or is formed on the plunger-like end of the central spindle, as shown at Fig. 3. The upper end of the central revolving spindle *g* has fixed to it a boss or disk *i*, carrying the upper cone or ring *i'* of a ball-race, whose lower ring or stationary part is attached to a casing *k* at the upper end of the stationary spindle *f*, the balls *j* of the bearing being fitted between the rings composing the ball-race.

Instead of a ball-bearing such as is shown at Fig. 2 the step-bearing may be formed by flat disks or washers or the bearing may be a fluid bearing.

By the arrangement described a step-bearing of much larger area is provided than could be placed within the outer revolving spindle *d* in the ordinary way, and liability of heating and breaking down is obviated.

The casing *k*, which incloses the step-bearing, is adapted to hold the oil or other fluid which serves to lubricate the bearing.

The stationary spindle *f* is secured at its upper end in the top block *l*, furnished with rubber buffers *m* in any usual way, and between the stationary spindle *f* and the upper end of the outer revolving spindle *d* is fitted a guiding-bush *n*.

Having now described the invention, what we claim, and desire to secure by Letters Patent, is—

1. In a centrifugal machine, the hollow stationary spindle *f*, the outer revolving spindle *d*, the internal central spindle *g* secured at its lower end to the said outer revolving spindle *d*.

2. In a centrifugal machine, the hollow stationary spindle *f*, the outer revolving spindle *d*, the internal central spindle *g* secured at its lower end to the said outer revolving spindle *d*, the step-bearing fitted overhead and formed between the upper end of said hollow stationary spindle and that of the said central spindle.

3. In a centrifugal machine, the combination of an outer revolving spindle, said spindle having a hollow upper end and a stationary spindle inserted in said hollow upper end, 5 an internal central spindle connecting said outer revolving spindle to the stationary spindle and revolving with the former.
4. In a centrifugal machine, the hollow stationary spindle *f*, the outer revolving spindle *d*, the internal central spindle *g* secured at its lower end to the said outer revolving spindle *d*, the step-bearing fitted overhead and formed between the upper end of said hollow stationary spindle and that of the said central spindle, the casing *k* inclosing the said bearing and adapted to hold the lubricant.
5. In a centrifugal machine, the hollow stationary spindle *f*, the outer revolving spindle *d*, the internal central spindle *g* secured at its lower end to the said outer revolving spindle *d*, the boss *i* keyed to said central spindle, the ring *i'* secured to said boss, an upper bearing-surface formed under and supporting said ring *i'*.
- 25 6. In a centrifugal machine, the hollow stationary spindle *f*, the outer revolving spindle *d*, the internal central spindle *g* secured at its lower end to the said outer revolving spindle *d*, the boss *i* keyed to said central spindle, the ring *i'* secured to said boss, a bearing-surface secured to and supported by said stationary spindle.
7. In a centrifugal machine, the hollow stationary spindle *f*, the outer revolving spindle *d*, the internal central spindle *g* secured at its lower end to the said outer revolving spindle *d*, the boss *i* keyed to said central spindle, the ring *i'* secured to said boss, and a casing *k* on the stationary spindle, provided with a bearing for said ring *i'*.
- 40 8. In a centrifugal machine, the hollow stationary spindle *f*, the outer revolving spindle *d*, the internal central spindle *g* secured at its lower end to the said outer revolving spindle *d*, the boss *i* keyed to said central spindle, the
- ring *i'* secured to said boss, a casing *k* on the stationary spindle, a raceway in said casing, and balls *j* in said raceway, adapted to support said ring *i'*.
9. In a centrifugal machine, the hollow stationary spindle *f*, the outer revolving spindle *d*, the internal central spindle *g* secured at its lower end to the said outer revolving spindle *d*, the boss *i* keyed to said central spindle, the ring *i'* secured to said boss, a casing *k* on the 55 stationary spindle, a raceway in said casing, balls *j* in said raceway, supporting said ring *i'*, and the top block *l* supporting said hollow stationary spindle.
10. In a centrifugal machine, the hollow stationary spindle *f*, the outer revolving spindle *d*, the internal central spindle *g* secured at its lower end to the said outer revolving spindle *d*, the boss *i* keyed to said central spindle, the ring *i'* secured to said boss, a casing *k* on the 60 stationary spindle, a raceway in said casing, balls *j* in said raceway, supporting said ring *i'*, and the top block *l* supporting said hollow stationary spindle, the buffers *m*, transmitting to the said top block the weight of the 70 said hollow stationary spindle.
11. In a centrifugal machine, the combination with the hollow rotating spindle, of a hollow stationary spindle secured to the usual top block, the said top block, an inner rotating spindle keyed to the outer spindle so as to revolve with it, and a step-bearing formed above the stationary spindle to support the rotating spindles as described.

In witness whereof we have hereunto set our 80 hands in presence of two witnesses.
